UNITED STATES PATENT OFFICE

126,749

DESIGN FOR A CLOCK

Herbert A. Rhodes, New York, N. Y.

Application February 21, 1939, Serial No. 83,145

Term of patent 3½ years

To all whom it may concern:

Be it known that I, Herbert A. Rhodes, a citizen of the United States of America and resident of New York city, county of New York, and State of New York, have invented a new, original, and ornamental Design for a Clock, of which the following is a specification, reference being had to the accompanying drawing, forming part hereof.

In the drawing:

Fig. 1 is a front elevational view of a clock showing my new design.

Fig. 2 is a side elevational view of the same.

I claim:

The ornamental design for a clock, substantially as shown.

HERBERT A. RHODES.
